(57) **CLAIM**

The ornamental design for a frame assembly with shelves, as shown and described.

DESCRIPTION

FIG. 1 is a first perspective view of a design for the frame assembly with shelves;

FIG. 2 is the first perspective view without environmental elements blocking a view thereof;

FIG. 3 is a second perspective view of the design thereof;

FIG. 4 is the second perspective view without environmental elements blocking a view thereof;

FIG. 5 is a first end view of the design thereof, wherein the opposite end view is a mirror image of the first end view;

FIG. 6 is a front view of the design thereof;

FIG. 7 is a rear view of the design thereof;

FIG. 8 is the rear view without environmental elements blocking a view thereof;

FIG. 9 is a top plan view of the design thereof;

FIG. 10 is the top plan view without environmental elements blocking a view thereof; and,

FIG. 11 is a bottom plan view of the design thereof.

The dashed lines in the drawings are shown for environmental purposes and form no part of the claimed design.
